CLAIM

The ornamental design for an outdoor musical instrument, as
shown and described.

DESCRIPTION

FIG. 1 is a top, front perspective view of an outdoor musical
instrument showing my new design according to a first
embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom, rear perspective view thereof;

FIG. 9 is a top, front perspective view of an outdoor musical
instrument showing my new design according to a second
embodiment;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a bottom, rear perspective view thereof;

FIG. 17 is a top, front perspective view of an outdoor musical
instrument showing my new design according to a third
embodiment;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top plan view thereof;

FIG. 23 is a bottom plan view thereof; and,

FIG. 24 is a bottom, rear perspective view thereof.

(Continued)

The evenly dashed broken lines in the drawings illustrate portions of the outdoor musical instrument that form no part of the claimed design.
